UNITED STATES PATENT OFFICE.

SIDNEY CLAIBORNE, OF FORT WORTH, TEXAS, ASSIGNOR, BY MESNE ASSIGNMENTS,
TO FRIGIDAIRE CORPORATION, A CORPORATION OF DELAWARE.

REFRIGERATING APPARATUS.

Application filed April 30, 1927. Serial No. 187,928.

This invention relates to mechanical refrigeration and particularly to mechanically refrigerated refrigerating devices for cooling various types of commercial refrigerator cabinets such as show-case refrigerators.

One object of the invention is to improve the efficiency of the transfer of heat from the air circulating within the cabinet to the refrigerant by preventing the frosting of the metal walls of the cooling unit while at the same time effecting satisfactory refrigeration.

More particularly it is an object of this invention to provide certain improvements in refrigerating apparatus having relatively large air flues surrounded by relatively narrow brine ducts so that heat may be transferred from the circulating air to the refrigerant more rapidly than heretofore. By using relatively large metal surfaces in contact with the circulating air the average temperature of the brine may be higher than in the conventional brine tank; consequently there will be less accumulation of frost upon these surfaces during the active periods of the operation of the refrigerating machine, and the metal surfaces will be defrosted during the idle periods. By providing relatively narrow brine passages between the metal heat transfer surfaces, substantially all of the brine is caused to circulate actively so that heat will be conducted from the metal walls to the refrigerant evaporator more rapidly than heretofore, with the result that the duration of the active period of the machine is reduced.

It is therefore apparent that refrigeration can be obtained more economically than heretofore, because the heat transferring media, the metal walls and the brine, are caused to operate more efficiently, and because the machine is not required to reduce the pressure upon the refrigerant to the low point necessary heretofore, since the average brine temperature is higher.

One object of the present invention is to minimize the accumulation of frost upon the metal heat-transfer surfaces of the refrigerating device during the active period of operation of the refrigerating machine while maintaining the device in relatively small and compact form. This object is accomplished by providing the main, narrow brine ducts with spur ducts or hollow fins projecting into the air flues of the re-

frigerating device. By using spur ducts the average temperature of the brine may be even higher than in the apparatus in which the spur ducts are not provided; consequently there will be substantially no accumulation of frost upon the metal heat-transfer surfaces to hinder the transfer of heat thereto even during the active period of machine operation. Although the heat transfer walls of the main and spur ducts are maintained at a temperature higher than the freezing point of the moisture which condenses thereon, the temperature of the circulating air will be sufficiently low for satisfactory refrigeration by reason of the presence of the relatively large metallic heat-transfer surface maintained free of frost at all times.

Further objects and advantages of the present invention will be apparent from the following description, reference being had to the accompanying drawings, wherein a preferred form of embodiment of the present invention is clearly shown.

In the drawings:

Fig. 1 is a vertical longitudinal sectional view of a show-case refrigerator cabinet equipped with a refrigerating device embodying the present invention; the device being shown partly in section on line 1—1 of Fig. 2.

Fig. 2 is a top view partly broken away, of the device; and

Fig. 3 is a sectional view on the line 3—3 of Fig. 2.

In Fig. 1, 20 designates a cabinet having solid insulating walls 21, 22 and 23 and other insulating walls provided by dead air spaces between a plurality of plates of glass 24 and 25. A partition 26 divides the interior of the cabinet into a cooling compartment 28 and a food or other display compartment 27.

The refrigerating device 30 includes a shell brine tank of tin-plated copper or galvanized iron and formed to provide a brine chamber 31 communicating with relatively narrow brine ducts 32, 33, 34, 35 and 36 which surround relatively large air flues 37 and 38.

The chamber 31 is provided with a tightly fitting removable cover 39 and encloses a cooling unit herein shown as an evaporator comprising a header or boiler 40 connected with refrigerant ducts 41. One end of the

boiler 40 extends through an opening 42 in the outside wall of the chamber 31 and is secured by a flanged collar 43 and a clamping disc 44 forming one end of the boiler. 5 Pipes 46 and 47 conduct refrigerant respectively into and out of the boiler 40. The chamber and ducts should be filled with brine or other low freezing-point liquid up to about one inch below the top of the container and the boiler should not be located 10 too low in the chamber 31, otherwise only the brine at the lower levels will effectively circulate and be cooled. Preferably the top of the boiler should be about one inch below 15 the level of the brine. It has been found that with a cooling unit located low in a deep tank, the brine above the coil does not cool down to the temperature desired, it remaining above the freezing point even 20 when the rest of the brine may be at or below freezing temperature.

The device 30 is supported above the bottom of the cooling chamber 28 and is spaced from the chamber walls and baffle 26 so that air may circulate freely around the unit as well as through its flues. The combined surface of the exposed vertical walls of the unit should at least be equal to the exposed surface of the block of ice which 30 would be required to cool the cabinet. By providing relatively narrow brine ducts and relatively large flue openings, a relatively greater exposed area may easily be provided by a refrigerating device which will occupy 35 a smaller space than the ice block. The space required by the device need be no more than approximately two-thirds of the cubical content of the cooling chamber 28, and may be slightly less if necessary to provide 40 at least three inches of space between the walls of the device and the cooling chamber walls so that air may circulate freely about and through the device. The matter of clearance is important, because frosting of 45 the tank and ducts tends to decrease the clearance and might even close it off entirely, preventing free circulation of the air. Unless the air can circulate freely adjacent the walls of the refrigerating device, it can 50 not absorb the heat from the air. For the same reason the flue openings should be at least four inches in width. As an example of construction of one form of the invention, if the tank and ducts are made of sheet 55 metal sufficiently thin to permit making the joints by lock-seaming and soldering, the width of the ducts need be only one inch or less. If heavier sheet material is required on account of the size of the cooling unit, 60 and the joints must therefore be riveted, the ducts may be two inches wide to allow for introducing riveting tools between the metal sheets forming the ducts. There is no object in making the ducts wider than one inch 65 except to facilitate manufacture. Gener-

ally, the brine ducts should be from about one to two inches wide and the flues preferably at least four times as wide as the ducts.

The circulation of air within the cabinet 70 is indicated roughly by the arrows 50, 51, 52 and 53. Shelves or other baffles (not shown) may be provided in the food chamber 27 for securing a fairly even distribution of the air circulating therein. 75

If more than one device is used in a cooling chamber, at least four inches and preferably six inches should be left between the tank for circulation and to prevent the space 80 from being stopped up with frost.

One of the features of the shell brine tank is the use of such a relatively large metal heat-absorbing surface adjacent which the air may circulate freely, that it is possible to effect satisfactory refrigeration by brine or other heat transfer medium working at temperatures higher than permissible in brine tanks used heretofore. Although, during the active period of operation of the refrigerating machine frost may collect upon 90 the metal surfaces, these surfaces will be defrosted during the idle period of the machine. Another feature is the circulation of brine through relatively narrow ducts between the metal heat-absorbing surfaces. Substantially all of the brine which is cooled by the evaporator is caused to circulate actively so that heat will be conducted from 95 the metal walls to the evaporator more rapidly than heretofore, with the result that the duration of the active period of the refrigerating machine is reduced. 100

The present invention solves the problem of preventing the accumulation of frost upon the metal surfaces surrounding the air flues during the operation of the refrigerating machine. The main brine ducts 33, 34, 35 and 36 and the chamber 31 are connected with spur ducts or hollow fins 60 and 61 which project, respectively, into flues 37 and 38. The metal, heat-absorbing walls of the main and spur ducts have a greater area exposed to the air circulating through the flues than in the cooling unit having no spur ducts. The brine is distributed within the flues so that heat from the air circulating through the flues will be quickly transferred to the brine. Consequently the temperature of the brine may be maintained above the freezing point while effecting satisfactory refrigeration. Besides operating as means for transferring heat to the brine, the hollow fins operate as plates upon which the moisture circulating with the air may be condensed without freezing. Since the fins prevent freezing of condensed moisture, the fins may be spaced relatively close within the flues in order to present the maximum heat transfer area, without danger of obstructing air circulation. 110

In my copending application Serial No. 187,927, filed April 30, 1927, I have disclosed the use of solid metal fins extending into the flues from the brine duct walls for 5 accomplishing the purposes disclosed herein. I have found that the number of spur ducts or hollow fins is less than the number of solid fins required to produce the results described herein.

10 Due to more rapid and effective circulation of the brine and to keeping the metal surfaces free of frost at all times, the average working temperature of the brine is higher than heretofore. Therefore the refrigerating machine may be operated more economically since it is not necessary to reduce the pressure upon the refrigerant in the evaporator to that low point required by apparatus in which the working temperature of the brine is lower.

15

20

The refrigerating device may be provided with horizontal or vertical flues according to the type of refrigerator cabinet with which they are intended to be used. Vertical flues are preferable, owing to the natural tendency of air to descend on being chilled. However, the invention is not limited to cooling units or tanks with vertical flues, as a refrigerating device with horizontal flues may be used advantageously in some types of cabinets; for example, a show-case cabinet not provided with a baffle to separate the food compartment from the cooling compartment.

35 Where the term "brine" is used in the specification and claims, it refers to any low freezing point liquid or solution which is suitable for transferring heat from the heat transfer walls of the device to the evaporator.

While the form of embodiment of the present invention as herein disclosed, constitutes a preferred form, it is to be under-

stood that other forms might be adopted, all coming within the scope of the claims which follow. 45

What is claimed is as follows:

1. Refrigerating apparatus comprising a shell tank having hollow walls adapted to form a narrow chamber and adapted to contain a refrigerating medium, said walls being arranged to form a flue and a heat absorbing member extending into said flue, said member being hollow and communicating with said chamber. 50 55

2. In a refrigerating device, a shell tank comprising a plurality of vertically extending hollow walls arranged to form a chamber adapted to contain refrigerating medium, said walls being arranged to form a vertically extending flue and a vertically extending heat absorbing member in thermal contact with a wall of said tank and extending into said flue, said member being hollow and communicating with said chamber. 60 65

3. In a refrigerating apparatus having chambers adapted to contain refrigerating medium air flues formed by the walls of said chambers, said air flues being provided with hollow heat absorbing members integral and communicating with the walls of said chambers. 70

4. Refrigerating apparatus comprising a shell brine tank, including a body portion adapted to contain brine, and a plurality of hollow walls forming circulating ducts communicating with the body portion, said walls forming a flue, said flue being provided with hollow heat absorbing members integral and communicating with said ducts, and a cooling unit disposed within the body portion for cooling said brine. 75 80

In testimony whereof I hereto affix my signature.
